UNITED STATES PATENT OFFICE

2,363,467

APPARATUS FOR DRYING

William Strobridge, Syracuse, N. Y., assignor to
 United States Hoffman Machinery Corporation,
 New York, N. Y., a corporation of Delaware

Application January 13, 1942, Serial No. 426,570

5 Claims. (CL. 34—48)

This invention relates to apparatus employed in dry cleaning, and more particularly to apparatus for drying materials which have previously been treated with an inflammable cleaning solvent. Such apparatus forms the subject matter of U. S. Patent 2,203,422 issued June 4, 1940, and U. S. Patent 2,217,153 issued October 8, 1940.

Patent 2,203,422 discloses a drying tumbler in which the materials to be dried are first subjected to the flow of air maintained at a safe maximum temperature relative to the flash-point of the solvent used, for a predetermined interval of time for the removal of the greater part of the solvent, then subjected to a flow of air at a temperature considerably higher than the flash-point for another predetermined interval of time, and finally subjected again to a flow of air at a safe temperature relative to the flash-point, to cool and complete deodorization of the materials and to bring the temperature within the dryer down to a point where the cycle of operation might immediately be repeated with safety. In that apparatus air is drawn through a heater, then through a rotating clothes containing cylinder by means of an electrically driven fan which discharges the solvent laden air to the atmosphere outside the tumbler. To insure safe operation, certain relays and interlocks are provided to make it impossible to start rotation of the tumbler drum unless the fan has first been set in operation by connecting the fan motor to a current source, and provision is made for automatically spraying the interior of the tumbler with steam and/or sounding a steam whistle in the event of current failure to the fan during operation of the tumbler.

It is an object of the present invention to provide improved apparatus of the character set forth.

To this end the electrically driven fan has been replaced by a fan driven by a steam turbine so that in the event of current failure there would still be a circulation of air through the tumbler, and any tendency to generate a flammable vapor-air mixture would be obviated. This avoids the necessity of sounding a whistle or injecting steam into the tumbler to prevent explosion or injury to the goods within the tumbler drum.

In order to make efficient use of the exhaust steam from the turbine, this is utilized in a primary heater which remains in operation throughout the entire drying cycle. This exhaust steam is the sole source of heat during the low heat and cooling periods of operation of the tumbler, and is controlled to maintain the air at the max-

imum temperature for those periods. The air issuing from the primary heater passes through a secondary heater which, during the high heat period of the cycle, is supplied with live steam to heat the air supply to the desired point above the flash-point of the solvent.

Other objects will be in part obvious and in part pointed out hereinafter.

The invention accordingly consists in the features of construction, combinations of elements, and arrangements of parts as will be exemplified in the structure to be hereinafter described and the scope of the application of which will be indicated in the following claims.

15 In the accompanying drawings in which is shown one of the various possible embodiments of my invention—

Fig. 1 is a front elevation of a tumbler embodying features of the present invention;

Fig. 2 is a right side elevation thereof;

Fig. 3 is a left side elevation thereof;

Fig. 4 is a rear elevation thereof;

Fig. 5 is a cross-section on line 5—5 of Fig. 4;

Fig. 6 is a top plan view of the rear portion of the tumbler showing the location of certain of the operating and control devices;

Fig. 7 is a perspective view thereof showing the top and right and rear sides of the tumbler;

Fig. 8 is a wiring diagram pertaining to the apparatus and devices shown in the preceding figures.

Similar reference characters refer to similar parts throughout the various views of the drawings.

Description of apparatus

Reference to Figs. 1 to 5 inclusive may be had for a general conception of the preferred form of apparatus. There is disclosed a tumbler comprising a outer shell or casing 10 having rotatably mounted therein a foraminous drum 11. The drum 11 is surrounded by an internal cylindrical shell 12 which encloses the drum for approximately three-quarters of the periphery thereof, the hinged outer shell door 13 at the front of the tumbler housing completing the enclosure. To the rear of the drum chamber near the top of the casing 10 there is provided a coil box 14 extending rearwardly through and beyond the rear plate of the casing and connecting with the rear plate of the casing by means of an opening 15.

The heater

Coil box 14 contains two heater units comprising a primary heater 16 and a secondary heater 17. Each of these heaters preferably is

of the fin type wherein the heat from the steam heating coils is radiated by suitable fins which surround the coils and provide a plurality of narrow passages for the flow of air, as indicated at 18 in Fig. 4. The primary and secondary heaters 16 and 17 are heated respectively by steam coils 19 and 20. The heater units are slightly spaced apart, as indicated at 21 in Fig. 5, to provide a temperature measuring chamber, the purpose of which will be explained herein-after.

Air from the secondary heater 17 is led to the top of the tumbler and admitted to the drum 11 through an opening 22 in the inner shell 12. The air outlet from the drum chamber is through an opening 23 at the bottom of the shell 12, opposite the opening 22. The air thus passes into the lower part of the tumbler casing beneath the drum chamber, where there is located an exhaust fan 24 having an air inlet 25 and outlet 27, the latter projecting through the rear wall of the casing. The fan is driven, in the present embodiment, by a suitable steam turbine 28, see Fig. 7, suitably connected to a live steam supply line 30. The fan serves to draw air through the opening 15 over both coils 19 and 20, then through inlet 22, down through the drum chamber, and by way of outlet 23 into the fan chamber from which it is exhausted to atmosphere. An unbalanced damper 29 is pivotally mounted in the fan discharge conduit 27 for a purpose which will be referred to in connection with the wiring diagram and the description of the operation of the tumbler.

Steam piping

The steam piping to the coils 19 and 20 may best be understood by reference to Fig. 7. The steam line 30 dropping down from above passes through a manually operated main shut-off valve 31 and then on below to a T 32. Below the T this main line goes to the upturned opening of a T 33, and then continues down from the said T to the inlet 34 of the steam turbine 28. From the outlet 35 of the turbine an exhaust steam line connects with a T 36 and then discharges through a suitable back pressure valve 37 to the atmosphere, or, if desired, to the heating system of the building in which the tumbler is located. The side outlet of the T 33 is connected to a hand operated valve 40 which connects with a steam spray pipe 41 located inwardly of the secondary heater 17 in the air passage leading to the tumbler drum.

From the T 32 a live steam line connects through the lever operated valve 38 directly with the inlet of the secondary heater coil 20. From the T 36 in the turbine exhaust line a low pressure steam line runs through the thermostatically operated valve 43 to the inlet of the primary heater coil 19. The thermostatic valve 43 is controlled in its operation by a bulb 44 located between the primary and secondary heaters in the chamber 21.

The outlet pipe 46 of the high pressure coil 20 passes through a swing check valve 47 and a high pressure steam trap 48 to any suitable return pipe of the steam heating system. A by-pass in this line contains a suitable thermostatic air venting valve 49. The outlet pipe 46' of the low pressure coil 19 is similarly equipped with a swing check valve 47', a low pressure steam trap 48', and an air venting valve 49'.

Steam valve 38 in the live steam line to the secondary heater coil 20 is operated automati-

cally by means of a lever 39 connected by means of a link with a crank mounted upon the shaft of the half-turn motor F, see Figs. 4 and 5. Thus full steam to the inner coil 20 is controlled by operation of the half-turn motor. As described above, a thermostatically controlled valve 43 controls the flow of turbine exhaust steam to the outer or primary coil 19. The diaphragm chamber of valve 43 is connected by means of tubing to the bulb 44. Thus the operation of the valve 43 is controlled by the temperature of the air in the temperature measuring chamber 21 after the air has passed through the primary heater but before the temperature of the air has been influenced by the high pressure secondary heater.

Cylinder drive

The tumbler drum shaft 11' is journaled in bearings 51 mounted on brackets 52 secured to the side plates of the tumbler housing. Upon the shaft 11' is mounted a spur gear 53 driven by a pinion 54 mounted upon a jack shaft 55 forming part of a pulley and belt shifting header assembly, as best seen in Figs. 1, 3 and 4, in which the jack shaft 55 is shown to be rotatably mounted in a pair of bearings 56, 57 carried by a header bracket or arm 58. This bracket is bolted to the side of the tumbler housing. The jack shaft 55 carries a tight pulley 59 and a pair of loose pulleys 60, 61. Also loosely mounted upon the shaft 55 is a header worm 62 which has a pin-and-slot connection, not shown, with the hub of the loose pulley 61 so as to be driven thereby.

Mounted upon the header bracket 58 in coaxial relation to the shaft 55 is a header arm assembly comprising the support 63, to which is pivotally connected the belt shifter fork 64. The header arm assembly includes a worm gear 67 on support 63 meshing with the worm 62, and a reciprocating slide shaft 68 slidably and rotatably mounted at the upper end of the support 63 in a block 69. Projecting from the block 69 parallel to the shaft 68 is a guide rod 70. A weighted pin or header-fall 71 secured to and extending at right angles to the slide shaft 68 shifts with the slide shaft about its axis so that the pin 71 may engage the upper end of the shifter fork 64 when the pin 71 is swung in one direction to a horizontal position and, sliding along the upper surface of the shifter fork, eventually settle in the notch 72 formed in the upper end of the shifter fork. When swung in the opposite direction to a horizontal position, the pin 71 will be free of the shifter fork 64 but will engage one or the other of the beveled surfaces 73 on the block 69 and ride down to a neutral position.

Mounted loosely upon the slide shaft 68 in a position between the block 69 and the tumbler housing is a shifter sleeve 74. This sleeve is held against endwise movement upon the slide shaft in any suitable manner. The sleeve carries a forked arm 76 cooperating with the guide rod 70 to prevent the shifter sleeve 74 from rocking about the axis of the shaft 68. The shifter sleeve carries a shifter arm 77 extending in opposite directions above the belt pulleys and provided with belt guide blocks 78 and 79, each equipped with a belt guide 80. The belt guides are so disposed that when the shifter pin 71 occupies its center or neutral position, the two drive belts 81, 82 will be positioned upon the loose pulleys so that under these conditions no power will be transmitted to the tumbler drum. It will be noted that the belt 82 is direct and the belt 81 crossed whereby the shifting of one

belt off and the other belt on to the tight pulley will effect a reversal of the rotation of the tumbler drum. It will be understood that belts 81 and 82 connect with a suitable line shaft, not shown, and are of a width to enable them to drive the tight pulley without disengaging their respective loose pulleys.

The operation of the header assembly will now be briefly described. It will be noted that since the worm 62 is driven by the loose pulley 61, it will always rotate in the same direction irrespective of the location of the belts with respect to the tight pulley. Thus, also, the worm wheel 67 will rotate constantly in one direction. This wheel drives a crank pin 83 slidable up and down in a slot 84 provided for that purpose in the shifter fork 64. This rotation of the loose pulley produces constant oscillation of the shifter fork at a slow rate of speed. When the pin 71 does not engage the notch 72 in the upper end of the shifter fork, no motion will be transmitted to the belt guides, but when the pin 71 engages the notch 72 it will cause the slide shaft 68 to reciprocate slowly. This action will periodically shift the drive belts and reverse operation of the tumbler drum. For a fuller description of this header construction, reference may be made to the above mentioned Patent No. 2,203,422.

Mechanically controlled mechanism

Referring again to the drawings, mechanical means for setting the tumbler in operation to begin the drying cycle will now be described. In the position of the parts shown in Fig. 3, the condition of the apparatus is that which would obtain after a batch of material has been placed in the drum and the shell door closed. Under these conditions the shell door cannot be re-opened or the header-fall brought into engagement with the shifter fork to start rotation of the drum until after the exhauster fan has been started, to make certain that there is an active flow of air through the tumbler. It may occur, at the start of a day's work, that the door will be closed and locked in the position shown in Fig. 3, when, as will be shown hereinafter, it will be necessary first to set in operation the steam turbine driven fan before it is possible to open the shell door for the loading of the drum. But if the door should be open prior to starting the fan, the drum may be loaded and thereafter the door closed, but no further operation can then take place until the fan has been started.

The means for shifting the header-fall into or out of engagement to cause belt drive of the tight pulley on the jack shaft comprises an operating lever 89 which with other operating parts is mounted upon a cast bed-plate 90 bolted to the side sheet of the tumbler housing. Operating lever 89 is pinned to a shaft 91 rotatable in a bearing forming part of said bed-plate casting. Attached to one end of the operating lever is a roller 92 adapted, when the lever 89 is thrown to engage the belt shifting header-fall in operating position, to come in contact with a switch operating arm 93, moving said arm to shift a switch A to initiate the operation of certain automatic controls, as will be explained hereinafter.

Pinned to the shaft 91 in proper angular relation to the lever 89 is an arm 94, connected by a link 95 to a multiple interlock member 96 which is free to turn about a shaft 97 mounted in bed-plate casting 90. Interlock member 96 is provided with three radiating portions num-

bered, respectively, 96¹, 96² and 96³. Two of these projections serve strictly as mechanical interlocking elements. The other projection, namely 96³, is connected by an adjustable link 98' to an operating arm 98 pivotally connected to a gear segment 99, see Figs. 3 and 4, rotatably mounted on a pin 100 which is carried by a part of the header bracket 58 in the following manner. Rising from the inner jack shaft bearing 56, is a fixed bracket 101. Mounted upon this fixed bracket by means of bolts is an adjustable bracket 105 which is secured to the fixed bracket by means of bolts which pass through arcuate slots in the fixed bracket whereby the adjustable bracket may be adjusted radially about the header jack shaft 55. The adjustable bracket 105 is provided with a seat for the pin 100, and also with a bearing 106 for the extruded hub 107 of a pinion 108. This pinion meshes with the gear segment 99 mounted, as described, upon the pin 100. Extruded hub 107 of pinion 108 is prevented from endwise movement by means of a set collar 110 and is provided with a coaxial bore, not shown, through which the reciprocating shaft 68 is free to move. Portions of this extruded hub diametrically opposite each other are removed to form long slots 111, providing driving surfaces against a pin 112 fastened through the shaft 68. Thus when the gear segment 99 is moved by endwise shifting of the link 98', the resulting movement of pinion 108 and its extruded hub rotates shaft 68 by means of the pin 112, no matter at what point in its path of travel this pin is located. For a clearer disclosure of this structure, reference may be had to aforesaid Patent 2,203,422.

This movement accomplishes the 180° throw of the header-fall 71 and is the means for initiating or terminating association of the tight pulley 59 with one or the other of the driving belts 81, 82 and thus the rotation of the tumbler cylinder. It will be understood then that, when the operating lever 89 is thrown toward the center of the tumbler away from the position shown in Fig. 3, the toggle composed of the members 94, 95 straightens out and causes rotation of the interlocking member 96 about its axis of rotation, causing the arm 96³ to move and rock the gear segment 99 toward the front of the tumbler. The straightening of the toggle 94, 95 locks the operating lever in the engaged position of the belt shifter header, thus insuring that the tumbler drive will continue until the starting lever 89 is returned to its forward or disengaged position.

Safety devices associated with mechanical control mechanism

There will now be described means connected with this operating mechanism for preventing the opening of the shell door 13 when the belt shifter header is engaged and also preventing any actuation of the operating mechanism to start rotation of the drum when the shell door is open.

Referring to Fig. 3, it will be seen that the interlocking member 96 is provided with the projection 96', as mentioned above, which serves to form an interlock between the operating lever 89 and the shell door 13. This projection cooperates with a camlike abutment member 123 mounted to move about the axis of the shell door 13. With the lever 89 in the header disengaged position, as shown in Fig. 3, there is no obstruction to the opening and closing of the door 13 due to the projection 96', but it will be understood

that when the door is open a portion of the abutment 123 lies in the path of projection 96', so that the operating lever cannot be thrown from the disengaged position to the engaged position of the header. Consequently the tumbler drum cannot be put into driven condition while the shell door remains open. On the other hand, when the shell door is closed and the operating lever 89 is in its rearward or header engaged position, the projection 96' of the interlocking member lies in the path of another portion of the camlike abutment 123, making it impossible to open the shell door. This arrangement thus makes it impossible, once the drying cycle has started, to introduce goods freshly laden with solvent and thus upset the control of the air-vapor mixture within the tumbler, a very necessary safety precaution.

Now, since, as will be shown hereinafter, it is impossible that the starting lever 89 be put into engagement position unless current is being supplied to the electric control devices, herein-after referred to, which first necessitates initiating operation of the fan by supplying steam to the steam turbine, it follows that the dryer cylinder cannot be set in operation until after the fan is started.

As will be explained in connection with the wiring diagram, the main electric line through the magnetic starter includes a switch R which is mounted upon the back sheet of the tumbler casing, see Fig. 3, and which is preferably a tilting mercury switch adapted to prepare the magnetic starter circuit so that, after the switch R is closed, the said circuit becomes manually operable when the fan is in operation. This results from the fact that when the fan is in operation the unbalanced damper 29 will be moved by the air stream from the fan, from its normal shut-off position closing off the discharge duct, to an open position which will not interfere with the air discharged from the fan. In the closed position of the damper the switch R is open, and in the open position of the damper the switch R is closed. Thus switch R is provided in the starting circuit for the control mechanism in order to be assured that the turbine is started when the steam is admitted to the same and that the fan is in operating condition.

Safety devices operable upon failure of steam to the fan turbine

Supported upon the bed plate 90, see Fig. 3, is a solenoid 125 to the core of which is attached a weight 126 of sufficient mass to cause the immediate descent of the solenoid core whenever excitation ceases. As will be more fully explained in connection with the wiring diagram, this solenoid is energized under normal working conditions upon the closing of the magnetic starter, which is indicated in the drawings by the letters MS and which is shown located on the tumbler housing in Figs. 1 and 3. It should be understood that operation of the magnetic starter closes the main switch which controls operation of the automatic cycle control devices and that the solenoid 125 remains energized as long as the main switch in the magnetic starter remains closed, or so long as turbine operation maintains the switch R closed, unless from other causes failure of current to the magnetic starter serves to open the main switch.

Pivottally mounted on the bed-plate 90 in operative relation to the solenoid weight 126 and projection 96' of the interlock member 96 is a

latch 127 having an arm 127' maintained by gravity in engagement with a shoulder 126' on the solenoid weight 126 and having another hook-shaped arm adapted to cooperate with the interlock 96' to prevent operating lever 89 being thrown to engaged position unless solenoid 125 has been energized which, as said above, can only occur if the tumbler fan is in operation and, as will be shown hereinafter, if the temperature of the air entering the tumbler from the heater is below a predetermined maximum. Thus it will be understood that latch 127 serves as an interlock against improper operation of the tumbler. When electric power is off, the solenoid 125 being de-energized permits the latch to swing into interlocking relationship with projection 96' so that, if the operating lever 89 be in the disengaged position, it will be impossible to throw it to the engaged position. Should it happen that the lever 89 being in engaged position and failure of current occur, the dropping of the solenoid weight will cause the latch hook to rest against the outer edge of the projection 96' so that as lever 89 is thrown to disengaged position, as it must be to continue further drying operations, for reasons which will appear later, the latch hook dropping under projection 96' interlocks therewith and prevents further operation of lever 89 until current has been restored.

Also pivotally mounted on the bed-plate 90 adjacent the solenoid is a latch 128 which functions only upon failure of current to prevent opening of the shell door 13 until current has been restored, which, as has been pointed out, can only be after the temperature of the air entering the tumbler from the heater falls below a predetermined maximum. Latch 128 cooperates at one end with a shoulder 126' on the solenoid weight 126, and at the other end is provided with a hook for interlocking action with a coacting abutment member 123' movable with the member 123 about the door hinge axis. When current fails, the dropping of the solenoid core, which has been holding the latch 128 out of engagement with door member 123', now permits latch 128 to swing under the action of gravity so as to interlock with the door member and prevent opening the door until current is restored. This latch never serves to prevent closing the door.

Thus it will be understood that irrespective of the period in the drying cycle that current failure may occur, the drying tumbler will be put out of operation and/or held out of operation until after current is once more flowing through the main switch to the control devices, which necessitates that the fan be in operation. Another safety element related to the solenoid 125 is a switch K which will be referred to hereinafter when its function will be explained in connection with the general operation of the tumbler.

The operation of the apparatus will presently be made plain by reference to the wiring diagram, Fig. 8, which shows so much of the original wiring diagram of Patent 2,203,422 as is pertinent to the present invention. For the purposes of this description, it will be assumed that there has been employed, in the predrying stages of the dry cleaning operation, a solvent having a flash-point slightly above 140° F., the temperature selected for carrying out the low heat stage of the drying operation during which from 60% to 70% of the solvent remaining in the clothes after centrifugal extraction is evaporated and driven off from the batch in the dryer drum. A high heat

period and a cooling period have been mentioned and have been found to be advantageous in carrying out the principles of the invention, but it should be borne in mind that variations of these stages of operation may be made without departing from the scope of the invention, since a more important consideration is this: that so long as there remains in the batch sufficient solvent to form an explosive mixture at any temperature, the dryer is incapable of operating above the predetermined safe maximum relative to the flash-point of the solvent used. Referring to Fig. 8, there will be found various control devices such as electrically operated timers, a magnetic switch contactor, and certain other switches not hereinbefore mentioned.

The magnetic starter MS has been mentioned, as have the half-turn motor P and the single pole double throw switch A which is operated by the operating lever 89. In addition to these control elements, there is a single pole double throw switch B which is operated by the half-turn motor concurrently with the operation by said motor of the live steam valve 38. It will be understood that the half-turn motor operates first to terminate the low heat period of operation, and operates again to terminate the high heat period of operation. After its second operation the half-turn motor will have returned to its initial position and be maintained in condition to control the operations of a succeeding drying cycle. The electrical connections to the half-turn motor are completed at the end of the low heat period through the operation of a low heat timer designated LHT, and the second operation to terminate the high heat period is controlled by a high heat timer designated HHT. A detailed description of the construction and operation of the half-turn motor and the timers LHT and HHT need not here be repeated since these are fully described in the aforesaid patent.

Wiring diagram

Again referring to Fig. 8, the wiring diagram will be seen to embrace the various pieces of equipment heretofore mentioned. It comprises the magnetic starter MS which is preferably provided with overload and low voltage protection, the single pole double throw switch A mentioned above as associated in operation with the header operating lever 89, the single pole double throw switch B operated by the half-turn motor, the two electric timers, the solenoid 125, the half-turn motor P, the fan actuated switch R, a thermostatic switch F which is controlled by the temperature of the air entering the tumbler from the heater, a magnetic contactor J interlocking center circuits, a single pole single throw manually operated selector switch M, and a single pole single throw switch K operated by the solenoid 125.

For economy in mechanical operation and wiring, switch B and other switches, not pertinent to the present invention, are enclosed in a single switch box 143, best seen in Fig. 5. Switches A and M are located in a single box 144, see Figs. 1 and 3. Also three pieces of equipment, the low heat timer, magnetic contactor J and the thermostatic switch F, are located together within a suitable box 163 mounted upon the rear portion of the top of the tumbler housing. This box is preferably equipped with a lock, not shown, since the low heat timer and thermostatic switch F are adjusted and set at the factory in accordance with the desired conditions of operation of the tumbler, and it is important that thereafter they

may not easily be tampered with. Mounted on top of this box are three pilot lights which indicate certain stages of the cyclic operation of the apparatus, but which will not be referred to again in this specification.

The thermostatic control switch F is operated by a suitable bulb 164, located in the air passage leading from the heater to the interior of the tumbler housing at a suitable location for measuring the temperature of the air after it has passed through both heater units and is about to be brought in contact with the materials within the dryer drum.

Referring to the wiring diagram, L1 and L2 indicate a single phase power line entering the magnetic starter MS. It will be seen that the line L1, at a point ahead of the magnetic starter, is connected by the switch contact arm A1 in the upper position thereof, through switch contacts A2, A3 to the starting button, marked "Start," of the magnetic starter. This connection only obtains when the header engaging lever 89 stands in its forward or disengaged position. Switch R, hereinbefore referred to, is located in a circuit between the stop button of the magnetic starter and the coil 166 of the starter so that, when the start button is pressed, a circuit to energize the coil 166 of this starter is established from line L1 through switch A, through the start and stop buttons of the magnetic starter, switch R, through the coil 166 to L2. Energization of the coil 166 will close the main switch contacts 167, 168 and thereafter the magnetic circuit is maintained by a jumper 169 connecting L1 into the starting circuit at a point between the start and stop buttons. Closing the main switch contacts 167, 168 provides a circuit L1A, L2A to the control mechanism including the timers and half-turn motor P. The line L2A contains a suitable thermal element 111 for overload protection.

It will be understood from what has been said that, to begin operation of the tumbler, the steam valve 31 must be open, admitting live steam to the turbine. This starts the fan in operation and, as soon as a suitable air flow has been set up through the heater and tumbler, movement of the unbalanced damper 29 will close the switch R. It will be understood at this time that the heater is under the control of the thermostatic valve 43. It will be seen also that after the closing of the switch R and the start switch of the magnetic starter, the main contacts of the magnetic starter will be closed and the line L1A becomes alive through one branch as far as the commutator P5 of the half-turn motor P, and through another branch as far as the thermostatic switch F.

The switch F is normally held in an open position at temperatures above the selected temperature at which the apparatus is to operate during the low heat period, as, for instance, 140° F. If, at the beginning of a cycle, the temperature stands below or at 140° F., the switch F will be closed and a circuit will be completed from L1A through switch K, through the coil of the magnetic contactor J and back to line L2A. Thus the magnetic contactor will be energized and, drawing up its core, will complete a circuit by way of switch contacts J3 and J4 through the coil of the solenoid 125 and will also complete a circuit by way of magnetic contacts J1 and J2 through its own operating coil. Thus the solenoid 125 will become energized and, by

the raising of its core, open the circuit through the switch K, so that thereafter the coil of the magnetic contactor J is maintained in an energized condition solely through the maintaining circuit including the contacts J1, J2.

Referring to Fig. 3 will show the switch K as located closely adjacent the solenoid 125 upon the side of the tumbler housing. The solenoid weight 126 is provided with a shoulder 126³ having a camming surface for engaging roller 174 carried by a lever 172 pivotally supported at 173 on the box of the switch K. This lever is provided with an adjustable bolt 175 adapted to engage the push button K1 of the normally closed switch K. This switch is merely a push button switch of a well known type biased normally to closed circuit condition. When the solenoid is engaged, the engagement of the adjustable bolt with the push button K1 opens the circuit through switch K, which no longer is needed since the magnetic contactor J is now self-maintained, as mentioned above.

It will be remembered that with the solenoid 125 de-energized, operation of the header engaging lever 89 to its header engaged position is prevented by reason of the engagement of the latch 127 with the interlock member 96². However, upon energization of solenoid 125 the interlock is removed and the header engaged lever 89 is released for manual actuation. Now, by throwing the lever 89 to its header engaged position, rotation of the tumbler drum is begun and the low heat stage of the drying cycle is initiated.

Low heat period of operation

As previously explained, when the operating lever 89 is thrown to start the drying cycle, this operates switch A through roller 92 and operating arm 93, causing the contacts A2, A3 to be broken, and the contacts A4, A5 to be made. Thus a live circuit is established to the switch B if the selector switch M is closed. This selector switch M is, as noted above, located in the same switch box 144 with the switch A, but is manually operated and is only opened when drying certain types of garments adversely affected by high temperatures. It will be readily understood that with the switch M open, the apparatus will not operate through the different stages of the drying cycle, but may be operated for an indefinite period of time under the conditions of the low heat period, with the temperature maintained at the temperature for which the thermostatic valve 43 is set.

Assuming, therefore, that the switch M is closed, the live circuit continues through contacts B4, B5 of switch B, to the low heat timer LHT by means of a line 176, and through the timer back to line L2A by means of wire 177. Thus the low heat timer is set in operation concurrently with the throwing of the operating lever 89. Having established previously by test that the low heat period shall be, say, ten minutes, after ten minutes have elapsed from the throwing of the operating lever 89, switch C in the low heat timer is closed, thus bringing the live circuit by means of wire 178 to the commutator segment P4 of the half-turn motor, and, as at this time the half-turn motor switch arm or brush P2 occupies the position shown in Fig. 8, the circuit will be completed through the half-turn motor to the line L2A.

The energization of the half-turn motor starts it upon its first half-revolution and, as soon as the

brush P2 passes from the segment P4 to the segment P5, the motor is connected directly in circuit with line L1A so that for the rest of its half-revolution the motor is energized from L1A through the motor coils and back to L2A. At the end of the half-revolution the brush moves off segment P5 onto segment P6 which at this time is not connected with the line L1. The half-turn motor accordingly stops at this point.

High heat period of operation

When the half-turn motor thus makes its half-revolution, it starts the high heat period of the drying cycle by opening valve 38 and admitting live steam to coil 20 of the secondary heater 17. It also operates switch B, as will be explained hereinafter. Thus the secondary heater, which up to this time has received no steam from any source, now receives steam to its coil 20 directly through the mechanically operated valve 38. The flow of steam in the exhaust line leading to the coil 19 of the primary heater 16 has, as was said above, been under the control of the thermostatic valve 43. The thermostatic valve will continue to operate so long as the temperature existing in the measuring chamber 21 does not exceed the predetermined temperature of the low heat period so that, after the operation of the mechanically operated valve, the primary heater receives whatever steam is passed by the thermostatic valve while the secondary heater becomes highly heated by the high pressure steam now passing through its coils. When the half-turn motor operated to change from low heat to high heat period, it operated switch B to break contacts B4, B5 and make contacts B2, B3.

When the live circuit through B4, B5 was broken, the low heat timer was de-energized and, through spring action, the timer was automatically reset to zero ready for the beginning of another cycle. The wire 179 now being alive through closure of switch contacts B2, B3, current flows to the high heat timer HHT starting the latter to control the period of high heat operation. After a time, the determination of which has been established by test, switch D in the high heat timer is closed completing a circuit through wire 180 to contact P6 of the half-turn motor which becomes energized and makes a second half-revolution back to its original position and, in so doing, closes the valve 38 thus cutting off the steam supply to the secondary heater. This restores the steam control to the condition desired during the ensuing cooling period and at the beginning of the next drying cycle. This reversal of the half-turn motor from high heat to low heat is the beginning of the final or cooling period of the cycle. The second half-revolution of the half-turn motor shifts the contact member B1 of switch B, breaks the circuit between B2 and B3, and reconnects contacts B4 and B5. Thus the high heat timer is de-energized and returns to zero position. During the high heat period of operation, the temperature of the air passing through the tumbler may be carried well above 200° F. because by this time only a small amount of solvent remains in the clothing and it is thus impossible to develop an explosive mixture in the drier.

If for any reason the header engaging lever 89 be thrown back to its disengaged position during the low heat period, the low heat timer will immediately be thrown out of action and will return to its initial position. Also, if the lever 89 be thrown to disengaged position during the high heat period, switch contact A1, by bridging contacts A2,

A3, will connect segment P6 of the half-turn motor in circuit, since the wire 180 is connected with contact A3, and effect the return of the half-turn motor to its initial position, ready to start a new cycle. The high heat timer would also return to its initial position through the shifting of the switch contact B1. In either case, should the operator immediately return the starting lever 89 to header engaged position, the whole cycle of operations would start again from the beginning.

Cooling period of operation

Under some conditions the cycle of operations might terminate here, but it has been found in practice that the time usually consumed to unload and reload the tumbler is insufficient to cool the tumbler to a temperature below the flash-point of the solvent, that is, below the maximum temperature established for the low heat period. It has been found desirable, therefore, in order to secure complete safety, to introduce a cooling period immediately succeeding the high heat period in order that the temperature of the air entering the dryer may reduce to the temperature setting of the thermostatic switch F.

During the cooling period a reduction of the temperature of the air entering the drum takes place, since the secondary heater is no longer operative. When the temperature is lowered to the setting of the thermostatic switch F, this switch closes and the apparatus is ready to begin a new cycle, after the operator has thrown his operating lever to disengaged position, opened the tumbler door, and replaced the load in the tumbler drum with a fresh load requiring drying.

As said above, switch B is actuated by the half-turn motor P. The switch B is a shiftable switch contained in the box 143 located adjacent the half-turn motor P at the top of the tumbler. Mounted on an extension of the half-turn motor shaft P2 is a cam 181 mounted on a shaft 183. Suitably supported in the framework of the motor assembly is an operating arm 184. At one end, arm 184 is equipped with a roller 186 contacting cam 181 and at the other end with an adjustable stud 187 contacting a push button of the switch B located in the switch box 143. Thus the cam 181 elevates the roller 186 and depresses the other end of the operating arm 184 when, at the end of the low heat period, the half-turn motor makes its first half-revolution, thus depressing the button of switch B and changing switch from its low heat position to its high heat position and, when the half-turn motor makes its second half-revolution to change the tumbler from the condition for high heat to the condition for cooling, the said cam moves the operating arm 184 to permit restoration of switch B to its original position with contacts B4, B5 made and contacts B2, B3 broken. A more complete disclosure and description of the timers, the half-turn motor, and the said cam operating mechanism for switch B as well as for certain signal controlling switches, omitted herein, may be had by reference to the said Patent 2,203,422.

In the operation of the tumbler the main shut-off valve 31 is manually operated and is used only to turn on or shut off the steam supply to the tumbler and to the steam turbine. The lever operated valve 38 is opened by the half-turn motor every time the automatic drying cycle changes from low heat to high heat conditions, and is closed again when the half-turn motor is called upon to change the tumbler operation from

high heat to the cooling stage. The thermostatic valve 43 may or may not be open when live steam is being supplied to the secondary heater, depending upon the temperature existing in the measuring chamber 21.

It should be noted that the steam valve 40 is included in the piping system only as a manual means for admitting live steam to the tumbler at the beginning of the operating cycle. This is done to make the operation of the tumbler conform, if found desirable, to a long established practice of some cleaners, by admitting steam for a few moments at the beginning of the operating cycle to prevent the accumulation of an abnormal amount of static electricity, a condition which might develop when drying such material as silk, particularly in cold weather.

It will be noted from the above that from the present construction are eliminated all devices for supplying steam to the interior of the tumbler or blowing a whistle in the event of current failure since, with a fan driven by a steam turbine, current failure would have no effect upon the flow of air through the tumbler unless simultaneously there were failure of steam as well. Live steam at a sufficiently high pressure for efficient operation of the turbine, say 90 pounds to the square inch, will provide exhaust steam at a suitable temperature to maintain the air leaving the primary heater at the desired temperature below flash-point. Should there be any excess of steam in the exhaust line so as to raise the temperature of the thermostatic valve to the closing point of said valve, the excess of pressure in the exhaust steam line will be taken care of by the back pressure valve 37 which, as was pointed out above, is located in the turbine exhaust line beyond the connection of that line with the thermostatic valve 43. The surplus of exhaust steam may be used for any low pressure accomplishment. Should there be a failure of steam to the turbine but not an electric current failure, the turbine and fan would stop and the unbalanced damper in the outlet duct of the fan would drop to its normal vertical position opening the circuit through the switch R. This would de-energize the coil of the magnetic starter and thus shut off current to the control system of the tumbler. As, under these conditions, no steam would be supplied to the heaters, the tumbler would gradually cool permitting the operator to remove the batch or not, as he might desire. However, since with the opening of the switch R the solenoid 125 would be de-energized, although it would be possible to move the operating lever 89 to its disengaged position and stop rotation of the tumbler, it would not be possible to raise the tumbler door 13 until current is again restored to the solenoid 125 and, as said above, this could not take place until the temperature within the tumbler falls to a point permitting the closing of the switch F.

As many possible embodiments may be made of the above invention without departing from the scope thereof, it is to be understood that all matter herein set forth or shown in the accompanying drawings is to be interpreted as illustrative and not in a limiting sense.

I claim:

1. In apparatus of the character set forth, in combination, a tumbler housing, a rotatable cylinder in said housing, driving means for said cylinder, control means for said driving means, means for operating said control means having cylinder operative and cylinder inoperative posi-

tions, a fan driven independently of said cylinder driving means for moving a current of air through said tumbler, an electric circuit including circuit controlling means operatively responsive to the passage of air through said fan, and electric means interconnected with said circuit cooperative with said operating means for said control means to prevent starting cylinder rotation unless said circuit control means is functioning to energize said circuit.

2. In apparatus of the character set forth, in combination, a tumbler housing, a rotatable cylinder in said housing, driving means for said cylinder operatively connected with a source of power, control means for said driving means, means for operating said control means having cylinder operative and cylinder inoperative positions, a driven fan operated by power from a source independent of the source of power for said cylinder drive for moving a current of air through said tumbler, a movable member located in the air stream of said fan, an electric circuit including circuit controlling means operable by said movable member, and electric means in said circuit cooperative with said operating means for said control means to prevent starting cylinder rotation unless said circuit controlling means is operating in response to the application of power to said fan.

3. In apparatus of the character described, in combination, a drying chamber, steam driven means having relatively high and low pressure steam supply and exhaust connections, a fan driven by said steam driven means for causing a current of air to pass through said drying chamber, heating means for said air comprising a primary heater and a secondary heater, means connecting said primary heater with said exhaust

connection, means connecting said secondary heater with said steam supply connection, and means independent of each other for controlling the steam supply to the respective heaters.

- 5 4. In apparatus of the character described, in combination, a drying chamber, steam driven means having relatively high and low pressure steam supply and exhaust connections, a fan driven by said steam driven means for causing a current of air to pass through said drying chamber, heating means for said air comprising a primary heater and a secondary heater, means connecting said primary heater with said exhaust connection, means including a control valve connecting said secondary heater with said steam supply connection, and time controlled operating means for said control valve.
- 10 5. In apparatus of the character described, in combination, a drying chamber, steam driven means having relatively high and low pressure steam supply and exhaust connections, a fan driven by said steam driven means for causing a current of air to pass through said drying chamber, heating means for said air comprising a primary heater and a secondary heater, means connecting said primary heater with said exhaust connection, means connecting said secondary heater with said steam supply connection, and time controlled operating means for said control valve.
- 15 25 6. In apparatus of the character described, in combination, a drying chamber, steam driven means having relatively high and low pressure steam supply and exhaust connections, a fan driven by said steam driven means for causing a current of air to pass through said drying chamber, heating means for said air comprising a primary heater and a secondary heater, means connecting said primary heater with said exhaust connection, means connecting said secondary heater with said steam supply connection, means for controlling the steam supply to said secondary heater, an electric circuit including automatic devices to effect operation of said controlling means, a movable member located in the air stream of said fan and movable by said air stream, and means in said electric circuit operable by said movable member to render inoperative said electric circuit and included automatic devices.
